DESIGN FOR AN EARRING ATTACHMENT DEVICE

Clarence B. Haegert, Coffeyville, Kans.

Application February 4, 1947, Serial No. 136,667

Term of patent 7 years

(Cl. D45—9)

To all whom it may concern:

Be it known that I, Clarence B. Haegert, a citizen of the United States, residing at Coffeyville, in the county of Montgomery and State of Kansas, have invented a new, original, and ornamental Design for an Earring Attachment Device, of which the following is a specification, reference being had to the accompanying drawings, forming part thereof.

In the drawings—

Fig. 1 is a front perspective view of an earring attachment device, showing my new design with the clamping screw omitted;

Fig. 2 is a side elevational view of the device as shown in Fig. 1;

Fig. 3 is a front perspective view of the earring attachment device; and

Fig. 4 is a vertical sectional view of the device as shown in Fig. 2 with the clamping screw added.

I claim:

The ornamental design for an earring attachment device, as shown.

CLARENCE B. HAEGERT.
